H. E. MAURER, JR.

RADIATOR CAP.

APPLICATION FILED OCT. 30, 1920.

1,431,123.

Patented Oct. 3, 1922.

UNITED STATES PATENT OFFICE.

HENRY E. MAURER, JR., OF SPRINGFIELD, ILLINOIS.

RADIATOR CAP.

Application filed October 30, 1920. Serial No. 420,749.

To all whom it may concern:

Be it known that I, HENRY E. MAURER, Jr., a citizen of the United States, residing at Springfield, in the county of Sangamon and State of Illinois, have invented a new and useful Radiator Cap, of which the following is a specification.

The invention relates to caps for the radiators of internal combustion engines, and particularly relates to radiator caps in conjunction with which devices known as "moto-meters" are used to indicate the temperature existing in the radiator.

It is common to attach moto-meters to the detachable caps of radiators. The moto-meters are separate articles of manufacture, readily saleable as accessories to various radiators, and being of considerable value, are often stolen. The fact that the caps commonly used may be quickly unscrewed, carrying the moto-meters with them, makes theft easy and detection difficult.

The purposes of the invention are: to provide a radiator cap permanently attached in the neck of the radiator and adapted to securely hold a moto-meter so that it cannot be detached from the radiator cap; to provide a radiator cap having an inclined duct extended forwardly beyond the front end of the radiator in such position that the level of the water in the tank may be viewed through the duct and in such position that water spilled while filling the radiator will not fall on and mar the radiator; to provide means for holding the moto-meter so that it will always face directly rearward; to provide as an integral part of the cap, an upwardly extended duct-member in such relation to a moto-meter supported on and having a stem extending into the cap, the moto-meter cannot be given a complete rotation in an attempt to detach it, so long as the cap remains on the radiator; to provide means to prevent the detaching of the moto-meter by means of an instrument inserted through the duct; and to provide improved details of construction.

The invention is illustrated in the annexed drawing, to which reference is hereby made and will now be fully described and the novel features thereof will be recited in the claims.

Figure 1 is a front elevation of a radiator cap embodying my invention; Fig. 2 is a

vertical section through the radiator cap on the line 2, 2, of Fig. 1; Fig. 3 is a reduced top plan of the same radiator cap, the moto-meter being omitted; and Fig. 4 is a top plan of the detached duct closure. The same reference numerals designate the same parts in all the views.

The moto-meter 5, shown in the drawings, is of common construction, except that part of its screw is filed away to form a flat surface 19, for a purpose hereinafter explained. The moto-meter proper is not part of the present invention and therefore need not be described in detail.

The body or main structure of the radiator cap is a metal casting, preferably aluminum, on account of its lightness and the facility with which it may be attractively finished, and comprises in one piece a cylinder 6, a forwardly and upwardly inclined duct 7, an internal arched baffle plate 8, handles 9 used to rotate the radiator cap and a screw 10 adapted to engage the usual internal screw threads in the neck 28 of the radiator to which the radiator cap is to be applied.

The duct 7 has internal screw threads 12. The duct closure 13 has an integral screw 14 engaging with the screw threads 12 to detachably connect the closure with the duct, and also has radial wings 15 useful for rotating the closure.

The cylinder 6 has in its top a central opening 16 (Fig. 3) admitting of free insertion of the screw threaded stem 18 of the moto-meter 5 and also has a keyway 17. To adapt the moto-meter for use with the radiator cap a portion of the moto-meter stem 18 will be filed away to form a longitudinal flat surface 19. When the parts are assembled, the key 20 inserted in the way 17 will bear against the flat surface 19 to prevent rotation of the stem 18 in the opening 16. A soft metal disk 21 supports the moto-meter on top of the cylinder. A gasket 22 and a washer 23 surround the stem 18. A nut 24 screwing on the stem 18 prevents longitudinal movement of the stem in the opening 16.

A thimble 25 screws on the stem 18 and locks the nut 24.

Here it is to be noted that the arched baffle plate 8 extends downwardly a considerable distance and thereby restricts the

throat 29 of the duct so that any instrument which can be inserted through the throat will not be effective to rotate the nut 24, or to hold the nut so that the stem 18 5 may be rotated in the nut in an attempt to detach the moto-meter from the radiator cap.

Internally screw-threaded holes 30 in the wall of the radiator neck are registerable 10 with the holes 26 in the wall of the screw member 10.

When the radiator cap is in place on the neck 28, screws 27 will be screwed into the registering holes 30 and 26, to securely connect 15 the radiator cap with the neck; the outwardly projecting parts of the screws will then be cut off close to the outer surface of the neck and the ends of the stub screws will be finished smoothly so that they cannot 20 be rotated or withdrawn by any instrument external to the neck.

To supply water in the radiator the closure 13 will be removed and the water will be poured through the duct 7 into the radiator. 25

The stem 18 of the moto-meter 5 extends downwardly inside the radiator cap and is directly subject to changes of temperature in the radiator; hence the moto-meter will 30 accurately indicate the temperature and the moto-meter being firmly held facing the user, it is easy for him to take the reading of the meter.

The devices connecting the moto-meter 35 with the radiator cap are all inside the cap, and inaccessible from the outside; the cap itself is permanently attached to the radiator and the forwardly and upwardly extended duct admits of filling the radiator without 40 disturbing the moto-meter and also prevents any complete rotation of the moto-meter; hence the risk of damage to or theft of the moto-meter is reduced to the minimum.

Having fully described my invention,

what I claim as new and desire to secure by Letters Patent is:

1. A radiator cap comprising a cylinder having a terminal screw adapted to engage screw threads on the neck of a radiator, an upwardly extended and forwardly inclined 50 duct-member integral with the cylinder and having a throat communicating with the interior of the cylinder, a downwardly extended baffle plate integral with cylinder and contiguous to the throat of the duct, and a 55 detachable closure in the free end of the duct-member.

2. In an appliance of the class described, the combination of a radiator; a cylinder permanently attached to the radiator and 60 having on its top a central opening and a key-way; a duct communicating with said cylinder; a moto-meter having a stem fixed on said moto-meter and extending through said opening in the top of said cylinder; a 65 key in said key-way preventing rotation of said stem; securing devices preventing longitudinal movement of said stem; and a baffle plate at the juncture of said duct with said cylinder and preventing access to said 70 securing devices.

3. In an appliance of the class described, a radiator cap comprising a stationary cylindrical body having an upwardly and forwardly extended duct-member, in combination with a moto-meter mounted on the cylinder body in such relation to said upwardly extended duct-member that the duct-member 75 will prevent complete rotation of the moto-meter on said cylinder. 80

In witness whereof I have hereunto signed my name at Springfield, Illinois, this 27 day of October, A. D. 1920.

HENRY E. MAURER, Jr.
